(57) **CLAIM**

I claim the ornamental design for a door lever, as shown and described.

DESCRIPTION

FIG. 1 is a perspective view of a door lever embodying the invention.

FIG. 2 is a front elevational view of the door lever shown in FIG. 1.

FIG. 3 is a top plan view of the door lever shown in FIG. 2.

FIG. 4 is a bottom plan view of the door lever shown in FIG. 2.

FIG. 5 is a left side elevational view of the door lever as shown in FIG. 2; and,

FIG. 6 is a right side elevational view of the door lever as shown in FIG. 2.

The rear elevational view is not part of the claimed design and is not shown. The broken-line disclosure is for illustrative purposes only and forms no part of the claimed design.
